UNITED STATES PATENT OFFICE

EARLE W. GOODNOW, OF LANSING, MICHIGAN, ASSIGNOR TO THE "NEW-WAY" MOTOR COMPANY, OF LANSING, MICHIGAN.

LUBRICATOR FOR EXPLOSION-ENGINES.

1,037,239.

Specification of Letters Patent.

Patented Sept. 3, 1912.

Application filed December 6, 1911. Serial No. 664,168.

To all whom it may concern:

Be it known that I, EARLE W. GOODNOW, a citizen of the United States, residing at Lansing, Michigan, have invented certain new and useful Improvements in Lubricators for Explosion-Engines, of which the following is a specification.

This invention relates to improvements in lubricators for explosion engines.

In the operation of explosion engines, of the so-called twin or duplex type having opposed cylinders, which are lubricated by the splash system, frequently an excess of lubricant is carried into one of the cylinders causing the cylinder, spark plug and other parts to foul, interfering with the efficiency of the engine and requiring frequent cleaning.

It is the main object of my invention to provide an improved lubricating means of the splash type for explosion engines having opposed cylinders in which the parts are so arranged that the cylinders do not receive an excess or undesirable amount of lubricant.

Further objects, and objects relating to details of construction, will definitely appear from the detailed description to follow.

I accomplish the objects of my invention by the devices and means described in the following specification.

The invention is clearly defined and pointed out in the claims.

A structure which is a preferred embodiment of my invention, is clearly illustrated in the accompanying drawing, forming a part of this specification, in which:

Figure I is a vertical longitudinal section taken on a line corresponding to line 1-1 of Fig. II, one of the cylinders being shown in full lines. Fig. II is a transverse section taken on a line corresponding to line 2-2 of Fig. I. Fig. III is an enlarged detail section taken on a line corresponding to line 3-3 of Fig. II, showing the mounting of the splash finger 10. Fig. IV is a detail view taken on a line corresponding to line 4-4 of Fig. III.

In the drawing, similar numerals of reference refer to similar parts throughout the several views, and the sectional views are taken looking in the direction of the little arrows at the ends of the section lines.

Referring to the drawing, the cylinders

1-1 are mounted on opposite sides of the crank casing 2 to open into the same. The crank shaft 3 is provided with a pair of crank arms 4. The pistons 5 are connected to these crank arms by the connecting rods 6 and 7. The crank shaft casing is provided with a depressed or well-like lubricant reservoir 8. This reservoir is on the side of the cylinder, the down stroke of whose connecting rod 6 is away from the cylinder. The bottom 9 of the outer side of the crank shaft casing is inclined to drain into the reservoir. The connecting rod 6 is provided with a splash finger 10 which, as the crank shaft revolves, dips into the lubricant throwing it against the wall of the crank shaft casing toward which it moves on the down stroke. This finger is preferably adjustably mounted on the connecting rod bearing 11, the adjustment being effected by slotting the finger at 12 to receive the bolt 13. The object of the adjustment is to cause the finger to throw more or less lubricant, as desired. A shield 14 is provided for the other cylinder. This shield projects from the wall of the crank shaft casing toward which the splash finger moves on its down or splash stroke, the plate being disposed at the inner side of the reservoir to project toward the crank shaft. The shield 14 is curved forwardly at 15. This permits it to project as much as possible without interfering with the crank shaft. By thus arranging the parts, the lubricant is splashed against the wall 16 and sufficiently atomized and scattered about in the casing to effectively lubricate the parts, and, at the same time, the cylinders are protected so that they do not receive an excessive amount of the lubricant; that is, such an amount as interferes with their efficiency or would unduly foul the cylinders.

I provide the reservoir with a pipe 17 having a T 18 at its outer end. The T 18 is provided with plugs 19 and 20. By removing the plug 19 the reservoir may be drained completely or by removing the plug 20 it may be drained to the proper level. The reservoir may also be filled through the upper arm of the T 18. The full or used lubricant may be drawn off and the reservoir cleaned by flushing with kerosene or the like.

I have illustrated and described my improvements in the form in which I have em-

bodied them for the market. I am aware, however, that various modifications in structural details are possible. I do not attempt to illustrate such modifications herein as 5 they will no doubt be readily understood by those skilled in this art, but I desire to be understood as claiming my improvements specifically in the form illustrated, as well as broadly within the scope of the appended 10 claims.

Having thus described my invention, what I claim as new and desire to secure by Letters Patent is:

1. In a lubricating means for internal 15 combustion engines having a plurality of oppositely disposed cylinders, the combination with the crank shaft thereof; of a crank casing into which said cylinders open provided with a lubricant reservoir on the side 20 of the crank arm whose downstroke is away from its corresponding cylinder the bottom of the other side of the casing being adapted to drain into the reservoir; a splash finger 25 for such crank arm; and a shield for the other cylinder projecting from the wall of the crank casing toward which said crank arm moves on its down-stroke, said shield being disposed at the inner side of the reservoir. 30
2. In a lubricating means for internal combustion engines having a plurality of oppositely disposed cylinders, the combination with the crank shaft thereof; of a crank 35 casing into which said cylinders open provided with a lubricant reservoir on the side of the crank arm whose down-stroke is away

from its corresponding cylinder the bottom of the other side of the casing being adapted to drain into the reservoir; and a splash finger for such crank arm. 40

3. In a lubricating means for internal combustion engines having a plurality of cylinders, the combination with the crank shaft thereof, of a crank casing provided 45 with a lubricant reservoir on the side of the crank arm whose downstroke is away from the cylinder in alinement therewith, such crank arm being adapted to splash the lubricant, the other side of the casing being 50 adapted to drain; and a shield for the other cylinder projecting from the wall of the crank casing toward which said crank arm moves on its downstroke, said shield being disposed at the inner side of the reservoir. 55

4. In a lubricating means for internal combustion engines having a plurality of cylinders, the combination with the crank shaft thereof, of a crank casing provided with a lubricant reservoir on the side of the 60 crank arm whose downstroke is away from the cylinder in alinement therewith, such crank arm being adapted to splash the lubricant, the other side of the casing being 65 adapted to drain.

In witness whereof, I have hereunto set my hand and seal in the presence of two witnesses.
